GARMENT HANGER ATTACHMENT

Filed Sept. 22, 1930

Inventor

Harry G. Bliss

By *Clarence O'Brien*
Attorney

UNITED STATES PATENT OFFICE

HARRY GOULD BLISS, OF RICHFIELD SPRINGS, NEW YORK

GARMENT HANGER ATTACHMENT

Application filed September 22, 1930. Serial No. 483,668.

This invention relates broadly to garment hangers, having more particular reference to that type of garment hanger known as a "coat" hanger, and the primary object of this invention is to provide an attachment especially adapted for use with a hanger of this type, the attachment being adapted to yieldably retain on the hanger the garment suspended therefrom.

10 A still further object of the invention is to provide an attachment of a simple and inexpensive nature which is adapted for use in conjunction with any type of garment hanger and which may be readily applied thereto 15 without altering the construction of the hanger.

A still further object of the invention is to provide an attachment of this character which will not only operate to yieldably retain the garment on the hanger, but will also aid in so retaining the garment on the hanger as to prevent such displacement of the garment relative to the hanger as would possibly result in destroying the original shape of the garment.

25 A still further object of the invention is to provide an attachment of this character which will insure the retaining of the garment on the hanger when the hanger is being manipulated as is often required in displaying the article suspended from the hanger.

Other objects and advantages of the invention will become apparent during a study of the following description, taken in connection with the accompanying drawing wherein the single view illustrates, in perspective, a conventional type of garment hanger equipped with my improved attachment.

With reference more in detail to the drawing, it will be seen the attachment as used 40 with a conventional type of garment hanger known generally in the art as a "coat" hanger and which includes the usual preferably arcuate article supporting bar 1 and the suspension hook 2.

The invention or attachment per se is formed from a single length of wire or other suitable strong yet yielding material, the wire intermediate its ends being coiled to 50 provide a substantially spring-like vertically

disposed portion 3 adapted to be disposed about the shank of the hook 2. The opposite end portions 4 and 5 of the wire extend laterally from the coiled portion 3, and these end portions 4 and 5 may be bowed longitudinally to conform to the curvature of the supporting bar 1. The end portions 4 and 5 preferably extend along the upper edge of the corresponding portions of the bar 1, the opposite end portion 4 adjacent the coil 3 being offset as at 6 in order that said portion 4 may be disposed adjacent the upper edge of the bar 1.

Each of the opposite end portions 4 and 5 at their free ends terminate inwardly from the adjacent end of the bar 1, in depending substantially U-shaped terminals 6. One leg of each of the U-shaped retaining terminals 6 at the free end of the leg is bent laterally as at 7 to provide a stop extending transversely of the bar 1 and adapted to yieldably engage the upper edge of the bar 1. The so-formed stops 7 will be normally engaged with the upper edge of the bar 1 due to the end portions 4 of the attachment being bowed and as is apparent.

In using the attachment, the garment to be supported by the hanger is disposed over the bar 1 in the usual manner, so that the shoulder portion of the garment will be draped over the bar and a portion of said garment at said shoulder adjacent the end of the bar 1 will be confined between the U-shaped retaining elements 6 and an adjacent portion of the bar 1 as is apparent. Also, the lateral stops 7 will be disposed exteriorly of the garment to rest on the shoulder of the garment thus confining a portion of the garment between the stops 7 and the upper edge of the hanger bar 1.

The manner of manipulating the opposite end portions 4 and 5 for so retaining the garments and positioning the same on the hanger is thought apparent from the foregoing. However, by way of explanation, it may be herein stated, that, with the parts in the position shown in the drawing, the terminal 6 of either end portion 4 or 5, may be urged upwardly relative to the supporting bar 1, thus moving said terminal 6 out of fric-

tional engagement with the bar and the attachment may then be rotated in the arc of a circle relative to the bar 1. The garment may then be placed on the bar 1 in the usual manner, after which the attachment is again rotated, so that the terminal 6 of one of the end portions, for example the end portion 4, engages a portion of the garment for retaining the same between said terminal 6 and the adjacent portion of the bar 1. The terminal 6 of the remaining end portion, for example, the end portion 5 is then moved upwardly relative to the bar 1 and then urged transversely of, and over the upper edge of the bar 1 to be then sprung into place, through the inherent nature of the attachment, for engagement with the garment on the same side of the bar 1 as the first mentioned terminal 6, so that the parts are then in that position shown in the drawing, with of course, the garment being positioned on the hanger and retained thereon through the medium of the attachment as is apparent.

As an alternate, with the parts in the position as shown in the drawing, the terminals 6 may be moved out of engagement with the bar 1, by merely exerting an upward pull, or a pull on the attachment relative to the bar 1 at right angles to the bar thus moving the spring sleeve 3 longitudinally of the shank of the hook 2. The bar 1 is then free to receive the garment in the usual manner, after which the spring sleeve 3 is moved relative to the shank of the hook 2 and toward the bar 1 so that the terminal 6 of one of the end portions 4 engage the garment for clamping the adjacent portion of the garment between said terminal and adjacent end portion of the bar 1. The remaining end portion of the attachment, namely the end portion 5, is then moved relative to the sleeve 3 for placing the terminal 6 of the end portion 5 in its retaining position, which, as is apparent is the position shown in the drawing.

From the foregoing then it will be seen that the attachment swings either forwardly or rearwardly for locking the garment on the hanger. It is also apparent, that the attachment is capable of being moved relative to the suspension hook so as to accommodate different thickness of one or more garments on the hanger; and further, it will be noted that the attachment is removable and can be so removed from the suspension hook and hanger with ease and facility thus permitting the attachment to be manufactured separately and independently of the hanger and capable of application to substantially all styles and types of hangers so that in the event the particular hangers to which the attachment is applied, become broken or injured, the attachment may be removed from that hanger and readily applied to a new one.

It is thought that from the foregoing description taken in connection with the ac-

companying drawing a clear understanding of the construction, operation, utility and advantages of an invention of this character will be had by those skilled in the art without a more detailed description.

Even though I have herein shown and described the preferred embodiment of my invention, it is to be understood that the same is susceptible to changes fully comprehended by the spirit of the invention as herein described, and the scope of the appended claim.

Having thus described my invention, what I claim as new is:

In combination with a hanger wherein the latter includes a suspension bar and a supporting hook intermediate the ends of the bar, a resilient rod provided with a coil intermediate its ends, said coil being disposed about the shank of said hook for sliding and rotative movement relative to said shank, and the end portions of said rod extending in opposite directions from the coil, each of said end portions terminating in a lateral projection yieldably engaging one side of the supporting bar for yieldably retaining said coil against casual movement relative to the shank of said hook.

In testimony whereof I affix my signature.

HARRY GOULD BLISS.
